UNITED STATES PATENT OFFICE.

HERMAN F. WALTON, OF SOUTH BEND, INDIANA.

VARIABLE ELECTRIC SIGN.

1,231,821.

Specification of Letters Patent. Patented July 3, 1917.

Application filed December 31, 1914. Serial No. 879,970.

To all whom it may concern:

Be it known that I, HERMAN F. WALTON, a citizen of the United States, residing at South Bend, in the county of St. Joseph and 5 State of Indiana, have invented a certain new and useful Improvement in Variable Electric Signs, of which the following is a specification.

My invention relates to that class of devices adapted to flash illuminated signs for advertising or display purposes and provides means for producing any desired form of display writing on the electric signboard.

The object of my invention is to produce 15 a device whereby an electric signboard is caused to show a form display of lights similar to a form traced manually upon a specially constructed writing-board.

Another object of my invention is to provide 20 means for making said form display permanent as long as desired.

Another object is to provide means for making the form display interchangeable by lighting the back ground on the board and 25 leaving the outline of the form display dark, and by lighting the form display and leaving the back ground dark.

I attain these objects by the construction and devices illustrated in the accompanying 30 drawings, in which—

Figure 1 on Sheet 1 shows a general front view of the electric signboard and a diagrammatic representation of the equipment required to produce the variable display 35 signs upon said signboard.

Fig. 2 on Sheet 1 shows a sectional elevation of the parts of the equipment required and a diagrammatic representation of the wiring required for each individual 40 light unit on said signboard.

Fig. 3 on Sheet 2 shows a diagram of the electric circuit required for the operation of the signboard.

Fig. 4 on Sheet 2 shows a plan view of 45 a part of the writing-board upon which the form display is outlined by manual operation.

Fig. 5 on Sheet 2 shows an enlarged section of the equipment chamber illustrated 50 in Fig. 2 and is a section on the line 5—5 thereof.

Fig. 6 on Sheet 2 shows a sectional view of the instrument used for tracing the form display on the writing-board.

Fig. 7 is an elevation of means for actu-

ating the resetting mechanism, being an amplification of Fig. 5.

Referring to Figs. 1 and 2 on Sheet 1, I provide an electric signboard 1 with a plurality of electric lamps 2, closely set near 60 each other to cover the entire face of the signboard.

An equipment chamber 3 having provided therin a plurality of electromagnet coils 4 each adapted to actuate the armature 5 of 65 a tripping pawl 6, mounted in the bus bar support 7, and which holds in suspension the switch end 8 of a pivoted bar 9, mounted in the connector support 10, and having provided thereon an extension ear 11 which 70 may be acted upon by a suitably formed set bar 12 to restore said pivoted bar 9 in the suspended position. The set bar 12 is moved downward to act on extension bars 11 by manual or electrical means. For the 75 former a finger key 33 secured to a stem 33 may be used and for the latter a magnet 36 with a suitable push button and battery, not shown, may be employed. The stem 33 is attached to the set bar 12 and may be guided 80 in the upper wall of the equipment chamber 3 as shown and a spring 34 or equivalent means serves to automatically raise the bar after the ears 11 of all the devices have been pressed down to restore the members 9 85 to a raised position. A bus bar 13, is suitably supported in the equipment chamber 3 between the bus bar support 7 and the connector supports 10, upon which the switch 90 end 8 of the pivoted bar 9 makes electric connection when the armature 5 of the tripping pawl 6 is attracted by the coil 4, to which current is supplied by the circuit wire 14 from the battery 15, when the return circuit wire 16, to which is attached the tracing instrument 17, becomes a closed circuit, by passing said tracing instrument over the contact disks 18, which form with the insulating material 19, the tracing surface on 95 the writing-board 20.

Each of the contact disks 18 has provided thereon, a stem 21 extending through the writing-board 20 to the interior of the compartment 22 upon which said writing-board 20 is mounted, and has attached thereto the circuit wire 23, which forms the other terminal of the coil 4.

Referring to the circuit diagram shown in Fig. 3 on Sheet 2, it will be seen that each of the contact disks 18 forming a part of 110

the primary operating circuit comprising the circuit wire 23, the coil 4, the circuit wire 14, the battery 15, the return circuit wire 16 and the tracing instrument 17 forming contact with the contact disks 18, controls the 5 lighting circuit of each lamp 2 comprising a positive circuit wire 24 connected to a dynamo 25 or other source of current, and a negative terminal 26 leading therefrom to a switch 27 which is adapted to form electrical 10 connection with the contact button 28 attached to the circuit wire 29, which is electrically connected with the bus bar 13, or with the contact button 30 attached to the circuit wire 31 which is electrically connected 15 with the bus bar support 7 to which are pivotally mounted the tripping pawl 6.

When the tracing instrument 17 is traced over the contact disks 18, as is illustrated in 20 Fig. 1 on Sheet 1, each of the electrical circuits connected with said contact disks 18 causes the induction coils forming a part of the circuit, to attract the armature 5 of the tripping pawl 6, which operation releases 25 the switch end 8 of the pivoted bar 9, and causes same to drop on the bus bar 13.

When the switch 27, attached to the negative terminal 26 is brought into contact with the contact button 30, current will flow 30 through the current wire 31 to the bus bar support 7, and through the tripping pawls 6, which have the remaining pivoted bars 9 suspended thereon, from which the current is passed through the return circuit wires 32 35 to the lamps which form the back ground, and are thereby lighted leaving the display outline dark.

When the switch 27 is then brought 40 into contact with the contact button 28, the lamps forming the back ground will have their circuit broken and become dark, while those lamps forming the display outline will have their circuit closed, through the circuit wire 29 attached to the bus bar 13 upon 45 which the switch end 8 of the released pivoted bar 9 rests, and thus become lighted.

The circuits may thus be alternated at will and be the means of causing attraction 50 to the display. The pivoted bars 9 which have been released upon the bus bar 13 may be restored into their suspended position on the tripping pawl 6, by moving the set bar 12 down upon the ears 11 on said pivoted bars 9, after which a new display design may be 55 traced on the writing-board 20.

It will be seen from the general arrangement of the apparatus, that any desired design may be exhibited in either the lighted or darkened display thus producing an 60 unlimited means of exhibition without making any mechanical changes in the equipment.

Having thus described my invention, what I claim as new, and desire to secure by Letters Patent, is:—

65 1. In an electric display sign, means for

producing an electric form display by tracing the form thereof upon a suitable circuit closing device, and means for simultaneously controlling the entire back ground so as to make the same luminous when the form is 70 shown in dark outlines or dark when the form is luminous.

2. In an electric display sign, a signboard 75 consisting of a plurality of lamps, means comprising a contact surface upon which a display form may be traced for setting a series of primary circuit controlling devices, means for holding the said devices in position without effecting the display lamps said means also adapted to hold a form composed 80 of such lamps after its appearance on the board, and means for supplying current through selected groups of such devices to the corresponding lamps connected therewith.

85 3. In electric display signs, a contact surface upon which a display form may be traced, a plurality of circuit closing devices actuated by the operation of tracing a display on the said surface, a sign board, electric circuits connecting the closing devices and the sign board adapted to duplicate the traced form on the sign board, a source of current therefor, and a separate switch adapted to control the supply of current 90 either to the lamps composing the back ground of the form or those constituting the form itself thus changing the lamp groups to either a positive or negative display as 95 desired.

100 4. In an electric sign, means for tracing a display form upon primary circuit closing devices each provided with an electromagnet capable of actuating an armature adapted to control the individual lamps of a sign 105 board, a source of current, means for placing the lamps into arbitrary groups, and means for supplying current to the single lamps or the groups independently of each other so that the display form is produced on the sign board in a group of lighted lamps with a plurality of unlighted lamps forming the back ground, or to light the lamps forming the back ground group and leave the lamps representing the display form unlighted.

110 5. In an electric display sign a plurality 120 of lamps mounted on a signboard, a circuit connecting the lamps to a source of current, an individual return wire leading from each lamp to a control switch, an electromagnet adapted to operate the control switch, a primary circuit connecting the magnet to a battery, a writing board comprising a plurality of contacts formed flush with the upper surface of the board and corresponding in number and position to the lamps on the signboard each contact connected separately to the battery circuits, a tracing device connected to the battery circuit and adapted to close such circuit when tracing a display 125 130.

form on the writing board, and means for holding an invisible form without effecting the lamps said means also being adapted to hold a displayed form as long as desired.

- 5 6. An electric display sign comprising a sign board provided with a plurality of electric lamps, a circuit for conveying current to said lamps, a duplicate return circuit, a switch adapted to connect the source of current to either circuit, a controlling device adapted to connect each lamp to either return circuit, an electromagnet to operate the same, a circuit including the electromagnet, contacts on a writing board connected there-
- 10 rent to either circuit, a controlling device adapted to connect each lamp to either return circuit, an electromagnet to operate the same, a circuit including the electromagnet, contacts on a writing board connected there-

with, a circuit closing device adapted to 15 trace a display form on the writing board coöperating with the contacts so as to close said circuits and cause the intermediate mechanism to produce a like display form in lighted or unlighted lamps on said sign 20 board as desired.

In testimony whereof I hereunto affix my signature in the presence of two subscribing witnesses.

HERMAN F. WALTON.
